UNITED STATES PATENT OFFICE.

CHARLES L. H. DINKELBIHLER, OF CINCINNATI, OHIO.

METALLIC RAILWAY-TIE.

1,049,060.

Specification of Letters Patent. Patented Dec. 31, 1912.

Application filed August 7, 1912. Serial No. 713,774.

To all whom it may concern:

Be it known that I, CHARLES L. H. DINKELBIHLER, a citizen of the United States, residing at Cincinnati, in the county of 5 Hamilton and State of Ohio, have invented certain new and useful Improvements in Metallic Railway-Ties, of which the following is a specification.

The present invention relates to improvements in railway ties, the object in view being to provide a cheap, durable and practical metallic tie as a substitute for the conventional wooden tie in common use at the present time.

15 In carrying out the invention, it is contemplated to employ special rail-clamping means for facilitating the removal of the rail without interference with the tie, and also permitting ready removal of the tie 20 without disturbance of the rail.

With the above and other objects in view, this invention consists in the construction, combination and arrangement of parts, all 25 as hereinafter more fully described, claimed, and illustrated in the accompanying drawings, wherein:

Figure 1 is a view in elevation of a tie constructed in accordance with my invention and showing the same in application. Fig. 30 2 is a top plan view, a portion of the same being broken away to more clearly show the details of construction. Fig. 3 is a transverse sectional view taken about on the line 3—3 of Fig. 2. Fig. 4 is a fragmentary 35 view of the tie showing a modified form of recess or pocket for the rail-clamping means, and Figs. 5 to 9, inclusive, are sectional views showing the various forms of construction of tie contemplated by my invention.

40 In carrying out my invention, it is to be understood that the body portion of the tie is of metallic material, and the particular form of the same depends to a large extent upon the manufacturer's preference and the particular purposes to be subserved. Specifically, the body portion of the tie may be composed of channel plates, such as shown particularly in Figs. 1, 2, 3 and 6, or it may 45 consist of angle plates, as shown in Fig. 5. The channel plates, designated by the numerals 1 and 2, are secured together in any desired manner, such as by means of rivets or bolts, and at their upper portions constitute the rail bearing surfaces. At each 50 end portion of the body of the tie thus de-

scribed, I provide pockets or recesses formed by means of plates 3 which are secured at their lower edge portions to the web of the tie by means of bolts or rivets 4. The plates 60 3 are bent at an angle above the fastenings 4 so as to provide pockets to receive the clamping members 5 pivotally mounted upon the rivets 6, which latter pass through the plates 3 and the web portions of the 65 plates 1 and 2, affording an additional fastening means for these plates, as will be obvious as this description proceeds.

Adjacent the clamping members 5 which are mounted on opposite sides of the plates 70 1 and 2, are pivotally mounted the locking members 7, also located within the pockets above mentioned. The clamping members 5 are formed at their free ends with hooks 5' which are adapted to engage over the base 75 of the rail 8 at opposite sides thereof. When thus in engagement with the rail, the locking members 7 are swung upon their pivots 7', so as to abut against the outer edge portion of the locking members 5, as most 80 clearly seen in Fig. 1 of the drawings. The rail is thus positively held in place upon the tie in a predetermined position. It will be obvious that the plates 3 which form the pockets in which the rail-fastening means 85 above described are mounted, effectually house the same and prevent dirt from interfering with their proper action. The clamping members 5 and the locking members 7 when swung on their pivots to disengage 90 the rail, will lie below the surface of the tie and permit the same to be readily removed from beneath the rails in an obvious manner. I prefer to provide an opening 8' in the rail bearing surface of the 95 plates 1 and 2, into which may be inserted a pick or hook for the purpose of withdrawing the tie or moving it to adjusted position.

The channel plates above described are particularly adapted for mud tracks where 100 the drainage of the track is a matter of importance, since the plates may be readily tamped beneath the rail bearing surface as well as the base of the plates designated by the numerals 1' and 2', thus giving double 105 safety to the rails and affording better opportunity to drain the ends of the ties, as will be obvious to those skilled in the art to which the invention refers.

Under certain conditions, such as where 110 full ballasted tracks are found, the angle plate construction shown in Fig. 5 may be

employed, the body portion of the tie comprising the plates 9 and 10 having the rail bearing surfaces 9' and 10'. The rail bearing surfaces above mentioned may be corrugated, for stiffening purposes, as shown in the drawings, or formed with depending flanges, as shown in Fig. 9; said flanges being designated by the numerals 11 and 12. It will be understood that these plates may 10 be integrally formed, as shown in Fig. 8, depending upon the manufacturer's preference, as hereinbefore premised.

In Fig. 4, I have illustrated a form of plate wherein the body portion of the same 15 is pressed outwardly, so that when secured in operative position, the pressed portion will form pockets on the opposite sides of the rail in which the clamping or the locking means may be mounted.

20 The tie above described will not only give a good bearing for the rail and hold its surface and gage well, but by reason of the particular form of rail fastenings, it can be handled the same as the ordinary wooden 25 tie, the fastening means securely holding the

rail in position and preventing unauthorized tampering therewith, in an obvious manner.

Having thus described the invention, what is claimed as new is:

30 A railway tie comprising channel plates having a portion thereof pressed outwardly to form pockets, clamping members pivotally secured to said channel plates at opposite sides in the pockets aforesaid, and locking members pivotally secured to the plates in said pockets adjacent the clamping members and in spaced relation to each other, said clamping members having hooks at their free ends to engage over opposite 40 sides of the rail, the pivots of the members aforesaid passing through the plates to secure the latter together.

45 In testimony whereof I affix my signature in presence of two witnesses.

CHARLES L. H. DINKELBHLER.

Witnesses:

Roy J. HOLMES,
R. W. PILLING.
